UNITED STATES PATENT OFFICE.

ADIN W. MITCHELL, OF DIALTON, OHIO.

CARRIAGE-CURTAIN FASTENER.

SPECIFICATION forming part of Letters Patent No. 355,702, dated January 11, 1887.

Application filed July 12, 1886. Serial No. 207,796. (No model.)

To all whom it may concern:

Be it known that I, ADIN W. MITCHELL, a citizen of the United States, residing at Dialton, in the county of Clark and State of Ohio, have invented certain new and useful Improvements in Carriage-Curtain Fasteners, of which the following is a specification, reference being had therein to the accompanying drawings.

This invention relates to certain new and useful improvements in curtain-fasteners for vehicles; and it consists, essentially, of a plate adapted to be attached to either the lower part of the top frame or to the body of the vehicle, and having a spring hasp or loop, the end of 15 the plate having a projecting lip, and of a sleeve or staple through which the hasp is adapted to pass, and with which the lip is adapted to engage, the staple being carried by the curtain.

20 In the accompanying drawings, forming a part of this specification, and on which similar letters of reference indicate the same or corresponding features, Figure 1 represents a side elevation of my improved fastener, showing a portion of a curtain, and also showing the fastener applied to a portion of the top frame or body; Fig. 2, a side elevation; Fig. 3, a sectional view; Figs. 4, 5, and 6, views, respectively, of the inside of the fastener, of the outside, 25 and, in section, of the staple or sleeve; Figs. 7 and 8, views, looking at the outside and edge of the fastener, showing modified form of connecting spring with it.

The letter A designates a metallic plate having perforations or other means of attachment to either the body of the vehicle or to a desired portion of the frame-work of the vehicle-top, and provided at one end with a lip or projection, B. This plate is provided with a transverse pin, C, near the other end, being bent or otherwise formed into a loop, D, for the reception of the pin, and with a slot which is occupied by the spiral coils of the spring-hasp E, which are wound around the pin C. The 30 ends of the wire forming the hasp project from the pin C, and lie against the plate, as at F, while the other end constitutes a loop, G. The action of the spiral winding of the hasp is that of keeping the hasp normally in close 35 contact with the adjacent side of the plate when not engaged with the sleeve or staple on

the curtain, and with a tendency toward the plate when engaged with the sleeve.

The curtain is provided with a metallic or leather or other sleeve, H, by preference constructed of sheet metal, and having projections I, which serve to pass through the material of the curtain and to connect the staple therewith by being clinched over, as seen in Fig. 6.

If the sleeve is made of leather, it should be 60 stitched to the curtain.

By preference the sleeve is provided with a notch, J, within which the lip B of the plate fits, as seen in Figs. 2 and 3.

In fastening the curtain the sleeve is slipped 65 between the hasp E and the plate A by lifting the hasp slightly away from the plate. When the notched portion of the sleeve reaches the lip B of the plate, the lip drops into the notch and enters again into the hasp. Thus the connection is formed, the lip resisting any longitudinal strain tending to draw the curtain away from the fastening, and the hasp preventing the disengagement of the lip and sleeve. In disconnecting the curtain from the fasten- 70 ing it is simply necessary to draw the curtain from the lip B until its end clears the sleeve, when by moving the curtain away from the lip the latter will slide over the sleeve and the staple from within the sleeve. 80

It is noticeable that the necessity for cutting and working button-holes in curtains is avoided, the particular objection to which is their liability to wear larger and larger the longer they are used, and the consequent accidental unbuttoning of the curtain from the buttons used in connection with them on vehicles. 85

There are several ways, it is obvious, of fastening the hasp to the plate, and while the preferred way is that shown and described, as it avoids the use of solder, yet I do not wish to confine myself to that particular way. 90

The pin C preferably has a head on one end which fits against the edge of the plate, while 95 the other end is turned or bent slightly over the other edge of the plate. This construction prevents the pin from slipping out.

In Figs. 7 and 8 the plate A is shown bent over at K and extended back partly across 100 the bend D, and the coils of the loop are held within the bend by the portion which is ex-

tended back. The ends of the loop project through the plate at L and bear upon its outer face, so as to prevent the coils from revolving when the loop is sprung up.

5 I would have it understood that I am aware that pocket-book fastenings have been made with a plate and a yielding or elastic bent bar hinged to that plate. In such instance, however, the plate is not provided with a projecting 10 lip which engages the device to be fastened; nor does the hinged bar, as a consequence of the absence of said lip, act to keep the device which is engaged by the lip from becoming accidentally disengaged from it. Furthermore, 15 the bent bar is not provided with coils and with ends which project beyond the coils and engage the plate.

Having thus fully described my invention, what I claim as new, and desire to secure by 20 Letters Patent, is—

1. As an article of manufacture, the carriage-curtain fastener, consisting of a spring-hasp,

a portion of which is coiled and the ends of which project beyond the coil, and of a plate having a lip at one end and constructed at the 25 other with a bend into which the coiled portion of the spring is fitted, the projecting ends of the coil bearing against the plate and the other portion of the hasp bearing against the plate on the side next to the lip. 30

2. The combination, with a plate having a lip and bend, a slot, a pin, and a hasp wound about said pin and constructed to bear normally toward the plate on the side next to the lip, of the metallic sleeve or staple clinched 35 to the curtain and adapted to receive the hasp and to be engaged by the lip.

In testimony whereof I affix my signature in presence of two witnesses.

ADIN W. MITCHELL.
